UNITED STATES PATENT OFFICE

PHILIP E. MORRILL, OF WEBSTER GROVES, AND CHARLES V. BRADY, OF ST. LOUIS, MISSOURI, ASSIGNORS TO BEMIS BRO. BAG CO., OF ST. LOUIS, MISSOURI, A CORPORATION OF MISSOURI

METHOD OF TUBING CLOTH FOR BAGS AND THE LIKE

Application filed July 9, 1930. Serial No. 466,724.

This invention relates to a method of tubing cloth, and with regard to certain more specific features to such a method for tubing cloth adapted to be used more particularly in the manufacture of bags.

The broad object of the present invention is to perform a tubing operation on cloth or fabric such as burlap, for example; the resulting cloth tubing being adapted to be used generally for bags such as described in a co-pending application for United States Letters Patent of Charles V. Brady for fastening, Serial Number 441,264, filed April 3, 1930.

Among the other objects of the invention may be noted the provision of a method of tubing cloth or the like, said tubing being effected by applying to the cloth in an improved manner an adhesive so that certain new and useful results are attained in contradistinction to the old, disadvantageous methods of sewing.

Another object of the invention is to permit of the effecting of an adhesive operation on a reticulated material such as cloth or fabric without pressing adhesive into the resulting tube.

Another object of the invention is to provide a method of effecting the results herein described which may be carried out on an automatic machine without deleteriously affecting said machine or the product thereon.

Other objects will be in part obvious and in part pointed out hereinafter.

The invention accordingly comprises the elements and combinations of elements, and steps and sequence of steps, which will be exemplified in the method hereinafter described, and the scope of the application of which will be indicated in the following claims.

In the accompanying drawings, in which is illustrated one of various possible embodiments of the invention,

Fig. 1 is a top plan view of the machine used in carrying out the present invention;

Fig. 2 is a left side elevation of the machine;

Fig. 3 is a longitudinal section, taken substantially on line 3—3 of Fig. 1;

Fig. 4 is a cross section taken substantially on line 4—4 of Fig. 3;

Fig. 5 is a plan view of one unit of the product made according to the present method; and,

Fig. 6 is a cross section taken on line 6—6 of Fig. 5.

Similar reference characters indicate corresponding parts throughout the several views of the drawings.

It has been known to tube paper for bag forming purposes but we have found that the automatic methods heretofore used in that art are not applicable to the art of tubing cloth or fabric for bag forming purposes. The reason for this lies in the fact that the paper or like material for paper and similar bags is not reticulated, that is to say, any adhesive applied thereto is not forced therethrough; whereas with cloth or fabric, the adhesive passes through if no provision is made to prevent it, and such passage will cause opposite faces of the sides of the bag to adhere deleteriously or will deleteriously coat certain parts of the apparatus used.

Referring now more particularly to Figs. 1 and 2, there is illustrated at numeral 1 a frame which supports a platen 3 upon which the tubing is to be formed. At the receiving end of the machine is located a supporting shaft 5 for carrying a supply roll 7 of what will hereinafter be referred to as a web, said web comprising the material from which the tubing is made. The shaft 5 carries a pulley 9 with which a brake shoe 11 is adapted to operate for purposes of placing tension in the web as it is drawn through the machine. The brake shoe 11 is adapted to provide a predetermined tension under adjustment of a pressure adjusting screw 13.

Above the shaft 5, the frame 1 is extended to support idling feed rolls 15, 17 and 19 over which the web 21 is threaded and adapted to pass. From the last roll 19 the web passes downwardly beneath a directing shoe 23, the purpose of which is to direct the web into a tangential movement on and above the platen 3. Then the material passes

through creasing guides or shoes 25, so that the opposite edges or selvages thereof are brought into lapped juxtaposition as shown at the center of Fig. 1. Suitable smoothing plates 27 aid in bringing the opposite edges or selvages into proper overlapping juxtaposition.

It will be seen from the above that in order to close the seam which results from the juxtaposition of the edges or selvages, that either stitching must be applied, or some form of adhesive must be interposed to fasten the juxtaposed surfaces. The latter, more advantageous method is used herein and is accomplished by supporting a pasting roll 29 under the arch of the web as it passes over the feed rolls 15, 17, 19. This pasting roll dips into a container of adhesive 31, such as liquid latex and also presses against the fabric side of the edge of the web which is passing over the roll 19, the reaction for effecting a proper application being supplied by said feed roll 19.

A feature of this invention comprises the advantageous manipulation of the type of material used. The material is shown more particularly in Fig. 6 comprising a layer of reticulated fabric material 33 such as cloth (burlap) to which is adhered by an asphaltic material or the like, a layer of paper 35. This adhered fabric-paper combination is what comprises the web 21. The material is so placed in the roll 7 that the paper is inside, as indicated at numeral 37 in Figs. 2 and 3, and the cloth is outside, as indicated at numeral 39 of said Figs. 2 and 3. Thus the cloth side of the web is on the under or inside of the reach of arch formed by the web passing over the guide rolls 15, 17 and 19. This results in the pasting roll 29 applying adhesive 41 to the cloth side of the left hand selvage as shown in Fig. 4.

The right hand selvage comprises a bare strip of cloth 43 formed by having previously brought the paper liner 35 somewhat short of the edge of said cloth 33, it being understood that said liner reaches the edge of the other selvage of the web, or at least reaches the region to which adhesive is to be applied. Thus, as the left hand selvage 45 with the adhesive therebeneath is turned over to turn up the adhesive and brought beneath the unlined selvage 43, and the unlined or reticulated selvage 43 forced down on the selvage 45 with adhesive thereon, there results a joining action, the adhesive (latex) being forced outwardly through the reticulations or the bare cloth forming the selvage 43.

From what has gone before, it will be understood that in the case of the pasted, lined selvage 45, the paper lining is brought up to the edge of the cloth. Hence, when pressure is brought to bear upon the juxtaposed selvages (incipiently by the last of the plates 27 and finally by a roller 47), the adhesive is

forced upwardly or outwardly through the reticulations of the selvage 43 but is not pressed downwardly through the selvage 45, because said selvage 45 is lined by the paper 35 which originally was outside in the forming operations but is finally on the inside of the tubing. Thus opposite sides of the tubing are prevented from adhering.

The tubing and webbing is drawn through this machine by a set of rolls 49 driven from a main shaft 53 by suitable change gears 56. The shaft 53 is driven from a suitable source of power 55.

After passing through the driving rolls 49, the then flat, edge pasted tubing passes over a biased knife edge 57 with which cooperates at intervals with a second, non-biased, revolving knife edge 59 supported on a shaft 61 and driven by gears 63 from said main shaft 53. In order that the revolving knife 59 may be effective, it is mounted on a frame 65 on the opposite side of which is a counterweight 67 providing inertia effects for driving the blade 59 through its cutting action. It will be understood that the linear velocity of the blade 59 is approximately equal to or perhaps somewhat higher than the linear velocity of the tubing being cut. The biased arrangement of the lower, stationary knife 57 does not produce a biased cut, because the tubing is being moved as it is cut. Hence the cut is substantially right angular with respect to the direction of movement.

After the tubing is cut into predetermined lengths, depending upon the change gears used, it is delivered from the machine over a delivery roll 69, from whence it passes to a suitable receiving table 71.

The character of the finished product is indicated in Figs. 5 and 6, except it is to be understood in connection with Fig. 6 that the thickness of the joint or pasted seam is somewhat exaggerated for clarity. It is also to be noted that Fig. 6 is a view showing the appearance of a cross section when viewed from the delivery end of the machine. This figure illustrates certain of the points made hereinbefore, namely, that the adhesive 41 cannot be pressed through and into the tubing, because of the paper liner 35 beneath the selvage 45 but that it can be pressed upwardly through the reticulations of the unlined selvage 43.

It will be noted from Fig. 1, that the roller 47 after a short period of operation in contact with the seam becomes coated with adhesive and lint or the like, the adhesive having been pressed up through the unlined upper selvage 43, but this is an advantage, because as the material builds up on the roller at this region, the roller becomes more effective to flatten out the seam. This action also definitely forces the adhesive into the reticulation, both of the upper layer of the lower

selvage 45 and into the unlined selvage 43. This produces a particularly strong joint.

The cutting of the tubing being accomplished while the joint is undried permits 5 immediately piling the tube lengths such as shown in Fig. 5 and permitting them to dry while awaiting shipment. Thus no separate drying operation is necessary.

From the above it will be seen that we have 10 provided a continuous, automatic method for forming cloth or fabric tubes of predetermined lengths, from which bags may be subsequently formed. The new method includes among its advantages the use of a 15 fabric material providing strength, and a leak-proof liner adhered thereto. This liner is not porous nor reticulated as is the fabric. The liner in the automatic operation is placed against the reaction roll with which 20 the pasting roll cooperates so that said reaction roll 19 will not have adhesive applied thereto by said adhesive passing through the reticulation of the fabric, the liner preventing this.

25 Furthermore, the adhesive is applied in a wet condition to the outside of the material (the fabric side), the material as a web being subsequently manipulated to hold it so that the adhesive is externally located but is applied 30 at a lined portion of the fabric. Then and thereafter the opposite unlined selvage is brought over the prepared lined selvage or portion. Then by the roller pressure the adhesive is squeezed upwardly through the unlined, reticulated selvage, the pressure roller 35 incidentally receiving adhesive and building the same up into an advantageous bulge, which both aids in making increased pressure by capillary action or the like and ensuring 40 that the adhesive passes through the said reticulations. It will be understood that the same principles may be employed by applying adhesive to the unlined selvage and folding the other selvage to interiorly overlap the applied adhesive.

45 The biased-knife cutter operating in conjunction with the process described results in the advantages of having a complete operation on one machine without employing an intermediate drying step. The biased construction with the operation of the knife at substantially web speed or somewhat greater provides a practical means for insuring an accurate cut.

50 In some cases, as, for example, when the reticulated material (burlap) is of exceptional thickness, it may be desirable to apply the adhesive compound (latex) to the juxtaposed side of the unlined selvage as well as to the fabric side of the lined selvage. In seaming, then, the juxtaposed selvages each carry thereon a layer of adhesive. By such a procedure the amount of adhesive material in the finished seam is substantially doubled, and a more secure seam is thus ef-

fected. In order so to apply the adhesive to the unlined selvage, a second pasting roll similar to the roll 29 may be provided, in this case at the opposite end of the rollers 15, 17 and 19, and outside the arch of the web. The 55 seaming and cutting operations are unaffected by this additional adhesive layer.

In general, adhesive penetration of the outer (unlined) selvage of the seam to the exterior of the tubing is of little consequence, as 60 any of such adhesive which might exude has sufficient time to dry during further operations in the tube forming process. In some cases, however, it may be desirable to size or otherwise treat this exterior of the seam in 65 order to prevent penetration.

Drying of the seam, if desired, may be accomplished with facility by substituting for the roller 47 a heated roller or platen, or, by adding to the apparatus, subsequently to the 70 roller 47 in the sequence of operations, a heated roller or heated rollers, platens, or drums.

75 It is to be understood that latex is described herein as exemplary of adhesives of its general nature, and that other similar flexible adhesives may be employed with satisfactory results.

80 In view of the above, it will be seen that the several objects of the invention are 85 achieved and other advantageous results attained.

85 As many changes could be made in carrying out the above method without departing from the scope of the invention, it is intended 90 that all matter contained in the above description or shown in the accompanying drawings shall be interpreted as illustrative and not in a limiting sense.

We claim:

1. A method of forming tubing from fabric which comprises lining said fabric with the exception of one selvage, applying adhesive to the fabric side of the lined selvage, inclining the two selvages toward one another and joining the inclined unlined selvage to the fabric on the adhesive side of said lined selvage.

105 2. A method of forming tubing from fabric which comprises lining said fabric at least behind one selvage, applying adhesive to the fabric side of the lined selvage, inclining the two selvages toward one another and joining the inclined unlined selvage to the fabric on the adhesive side of said lined selvage.

110 3. A method of forming tubing from fabric which comprises lining said fabric with the exception of one selvage, drawing a web of said lined fabric from a supply, applying adhesive to the fabric side of the lined selvage, 115 inclining the two selvages toward one another with the adhesive of one selvage directed away from the lining and joining the inclined unlined selvage to the fabric of the lined selvage, whereby the adhesive perme- 120

ates the fabric of both selvages but is prevented by the lining of the lined selvage from entering the resulting tubing.

4. A method of forming tubing from fabric which comprises lining said fabric to include at least one selvage, drawing a web of said lined fabric from a supply, applying adhesive to the fabric side of the lined selvage, inclining the two selvages toward one another with the adhesive of said lined selvage directed away from the lining and joining the inclined selvages so that the lined selvage is interior, whereby the adhesive permeates the fabric of at least the lined selvage but is prevented by the lining of said lined selvage from entering the resulting tubing.

5. A method of forming tubing from fabric which comprises lining said fabric to include one selvage but not the other, drawing a web of said lined fabric from a supply, applying adhesive to the fabric side of the lined selvage, inclining the two selvages toward one another with the adhesive of said lined selvage directed away from the lining and joining the inclined selvages so that the lined selvage is interior, whereby the adhesive permeates the fabric of at least the lined selvage but is prevented by the lining of said lined selvage from entering the resulting tubing

20 and subsequently pressing together the resulting juxtaposed fabrics whereby the adhesive is forced outwardly through the fabric of the unlined fabric.

6. A method of forming tubing from fabric which comprises lining the fabric with the exception of one selvage, drawing a web of said fabric from a supply, applying an adhesive to the fabric adjacent its lined selvage, and folding said web longitudinally so that the unlined selvage is brought in contact with the adhesive.

7. A method of forming tubing comprising lining a fabric, drawing a web of said lined fabric from a supply, applying adhesive to the fabric adjacent one selvage, and folding said web longitudinally, so that the other selvage of the fabric overlaps the adhesive.

8. The method of tubing a web of reticulated fabric comprising providing the web with a non-reticulated longitudinal zone, drawing a supply of said web from a roll, applying adhesive to the fabric adjacent one selvage thereof and folding the web longitudinally to position the other selvage over the adhesive.

9. The method of tubing a web of reticulated fabric comprising providing the web with a non-reticulated longitudinal zone, drawing a supply of said web from a roll, applying adhesive to the fabric adjacent one selvage thereof and folding the web longitudinally to position the other selvage over the adhesive and pressing the joined selvages to force adhesive through the juxtaposed fabric areas.

In testimony whereof, we have signed our names to this specification this 21st day of June, 1930.

PHILIP E. MORRILL.
CHARLES V. BRADY.
